DESIGN FOR A CANDELABRUM OR LIKE ARTICLE

Severo E. Soria, New York, N. Y.

Application July 31, 1940, Serial No. 94,064

Term of patent 3½ years

To all whom it may concern:

Be it known that Severo E. Soria, a citizen of the United States and resident of New York city, in the county of New York and State of New York, has invented a new, original, and ornamental Design for a Candelabrum or like Article, of which the following is a specification, reference being had to the accompanying draw-

ing, forming part thereof, in which the single view is a perspective view of a candelabrum, showing my new design.

I claim:

The ornamental design for a candelabrum or like article, as shown.

SEVERO E. SORIA.
